UNITED STATES PATENT OFFICE.

OSCAR WILLIAM DUNHAM AND FRANCIS WILLIAM WILLIS, OF TORONTO, ONTARIO,
CANADA.

DESIGN FOR A TIRE.

49,958.

Specification for Design.

Patented Nov. 28, 1916.

Application filed August 16, 1916. Serial No. 115,299. Term of patent 3½ years.

To all whom it may concern:

Be it known that we, OSCAR WILLIAM DUNHAM and FRANCIS WILLIAM WILLIS, both British subjects, and residents of the city of Toronto, in the county of York and Province of Ontario, Dominion of Canada, have invented a new, original, and ornamental Design for Tires, of which the following is a specification, reference being had to the accompanying drawing, forming part thereof.

The figure is a plan view of the tread of the tire showing our new design.

We claim—

The ornamental design for a tire, as shown.

Toronto, August 12th, 1916.

OSCAR WILLIAM DUNHAM.
FRANCIS WILLIAM WILLIS.
